UNITED STATES PATENT OFFICE.

SWITS CONDÉ, OF OSWEGO, NEW YORK.

DESIGN FOR A KNIT SHIRT.

Specification forming part of Design No. **11,485**, dated November 4, 1879; application filed October 13, 1879.
[Term of patent 7 years.]

To all whom it may concern:

Be it known that I, SWITS CONDÉ, of Oswego, in the county of Oswego, in the State of New York, have invented new and useful Improvements in Designs for Knit Shirts, of which the following, taken in connection with the accompanying drawing, is a full, clear, and exact description.

The accompanying drawing illustrates my design as applied to the body of a knitted shirt, *a* denoting a plain or single colored stripe, and *b* a stripe composed of alternating transverse bars of two different colors, one of which is that of the plain stripe.

The stripes *a* and *b* are perfectly straight, and arranged alternately and parallel to each other, and vertically in relation to the garment.

What I claim as my invention, and desire to secure by Letters Patent, is—

The design for knitted shirts, consisting of the plain stripes *a* and the stripes *b*, the latter composed of alternating transverse bars of two different colors, one of which is that of the plain stripes, the said stripes being perfectly straight and arranged alternately and parallel to each other, and vertically in relation to the garment, substantially as described, and shown in the accompanying illustration.

In testimony whereof I have signed my name and affixed my seal in the presence of two attesting witnesses, at Syracuse, in the county of Onondaga and State of New York, this 8th day of October, 1879.

SWITS CONDÉ. [L. S.]

Witnesses:

E. LAASS,
C. BENDIXEN.
